A. SCHOY

DOOR JAMB MORTISE PLATE

Filed Nov. 10, 1925

UNITED STATES PATENT OFFICE

ARTHUR SCHOY, OF NEW YORK, N. Y.

DOOR-JAMB MORTISE PLATE.

Application filed November 10, 1925. Serial No. 68,051.

My improvements relate to the metallic mortise plates used on door jambs for the reception of the door bolts, and particularly to the type of jamb mortise plate in which provision is made for engagement with a spring latch bolt as well as with the usual lock bolt, although my invention is designed more especially for the improvement of the mortise for a spring latch bolt, the nose of which is bevelled in a manner well known in the art, and which is intended to slide over the face of the jamb mortise plate and to engage therewith automatically.

Owing to the bevelling of the noses of these spring latch bolts they are apt to fit loosely in their mortises, so that unless the lock bolts also are shot into the mortise plates there is a degree of looseness and play which may result in door vibration and rattling under variations of air pressure on opposite sides of the door, which it is the main object of my invention to obviate, and which I accomplish by means of an adjustable auxiliary shoulder plate for engagement with the flat locking side of a spring latch bolt, so that looseness or play of the said spring latch bolt in its mortise will be prevented, and a close fit insured between the parts involved.

To this end my invention consists essentially of an auxiliary shoulder plate mounted on the inner side of the door jamb plate adjacent to the spring lock bolt mortise by means which provide for its adjustment with relation thereto as hereinafter set forth, and described and claimed specifically,—a distinctive feature being the utilization, as a mount and support for my said auxiliary shoulder plate, of the usual lateral tongue extension of the jamb plate provided for engagement with the bevelled end of the spring latch bolt in the usual way.

In the accompanying drawings, I illustrate a practical embodiment of the essential features of my invention as applied to a door jamb plate made for the accommodation of both a door lock bolt, and a spring latch door bolt, although I do not limit myself in this respect, since my adjustable auxiliary bolt shoulder may be provided on a jamb mortise plate designed only for engagement with a spring latch bolt of the character designated, nor do I limit myself to the identical form and construction of parts shown herein by way of exemplifi-

cation, since changes may be made in minor details, and equivalent mechanical expedients resorted to with like results, and without departing from the spirit and intent of my invention in this respect.

With this understanding:

Fig. 1, represents a face view of a door jamb plate of the duplex bolt mortise type hereinbefore referred to, my auxiliary bolt bearing shoulder being in retracted position;

Fig. 2, is a view like unto Fig. 1, showing my auxiliary bolt bearing shoulder plate slightly advanced to contract the area of the mortise aperture;

Fig. 3, is a like view showing my auxiliary bearing shoulder still further advanced to contract the area of the mortise aperture;

Fig. 4, is a perspective view of the rear side of the door mortise jamb plate shown in the preceding figures;

Fig. 5, is a perspective view of my auxiliary bolt bearing shoulder plate;

Fig. 6, is a sectional detail, upon an enlarged scale, taken upon plane of line 6—6, Fig. 1;

Fig. 7, is a sectional detail, also upon an enlarged scale, taken upon plane of line 7—7, Fig. 1;

Fig. 8, is a sectional detail showing a modification.

In the type of door jamb mortise plate P, shown as embodying a practical adaptation of my invention, s, s, represent the holes for the screws by which the plate is secured to the door jamb, l the lock bolt mortise, and l', the spring latch bolt mortise, p, being the usual lateral extension of the mortise plate P, provided for contactual engagement with the bevelled nose of a spring latch bolt as heretofore, except that in the present case said lateral extension p, of the mortise plate P, has adjustably mounted on its inner side my auxiliary bolt bearing plate a.

This combination of my auxiliary bolt shoulder bearing plate a, with the lateral extension p, of the jamb mortise plate P, may obviously be effected by resort to various mechanical expedients, of which a preferred form is shown in this connection, consisting in inturning the horizontal edges of the lateral extension p, of the plate P, to form retaining flanges p', p', as shown more particularly in Figs. 4 and 6, of the drawings; in forming said extension p, with a horizontal bevel-edged slot p², and in pro-

viding a bevel headed binding screw *b*, for engagement with a female screw thread *a'*, formed for the purpose in said auxiliary plate *a*, as shown more particularly in Figs. 6 and 5 7, of the drawings, whereby the said auxiliary shoulder plate *a*, may be adjustably secured in position according to requirements.

The chamfered or bevelled nose of a 10 spring latch bolt is indicated at *x*, in Fig. 7, of the drawings, illustrating its co-relation to the lateral extension *p*, of the door jamb plate *P*, in sliding thereover.

In the modification illustrated in Fig. 8, 15 of the drawings, an alternative structure of clamping means is shown in which the auxiliary shoulder plate *a*, is formed with a screw stud *a²*, for engagement with a nut *n*, the circular edge of which is bevelled to fit the bevel of the slot *p²*, in the jamb plate.

20 No claim is made broadly to a flanged plate in this connection.

What I claim as my invention and desire to secure by Letters Patent, is:—

1. A door jamb plate having a lateral extension having its horizontal edges in-turned to form parallel retaining flanges, an auxiliary bolt shoulder bearing plate slidably fitted between said flanges, and means passed through said bearing plate and into said extension between said flanges. 25

2. A door jamb mortise plate having a lateral extension with its horizontal edges in-turned to form parallel retaining flanges, an auxiliary bolt shoulder bearing plate slidably fitted between said flanges, the said extension being formed with a horizontally extended bevel-edged slot, and a screw member engaged in the bearing plate and having a beveled head engaged in said bevel-edged slot. 30 35

ARTHUR SCHOY.
